J. S. BARTLEY

GRINDING MILL

Original Filed Feb. 8, 1919

FIG. 1

FIG. 2

FIG. 3

INVENTOR.
J. S. BARTLEY.

J. S. Bartley
BY
ATTORNEY.

UNITED STATES PATENT OFFICE.

JOSEPH S. BARTLEY, OF DENVER, COLORADO.

GRINDING MILL.

Application filed February 8, 1919, Serial No. 275,787. Renewed May 14, 1924.

To all whom it may concern:

Be it known that I, JOSEPH S. BARTLEY, a citizen of the United States, residing at Denver, in the county of Denver and State 5 of Colorado, have invented certain new and useful Improvements in Grinding Mills, of which the following is a specification.

This invention relates to improvements in ball grinding-mills and its object is to provide in a mill of this type, means which operate by its rotary movement to automatically classify the ground product according to the sizes of its particles and return the oversize to the feed-end of the mill 15 for further grinding.

With this object in view, I provide a construction which in its preferred form is shown in the accompanying drawings in which—

20 Figure 1 represents a longitudinal section of the improved mill,

Figure 2, a transverse section on the line 2—2, Figure 1, and

25 Figure 3, a similar section taken on the line 3—3, Figure 1.

Referring to the drawings by numerical characters of reference which in the several views designate corresponding parts, 2 indicates a cylinder which by means of axially 30 alined trunnions 3 and 4 at its opposite ends, is rotatably mounted in pillow blocks on standards 5 and 6.

The cylinder is composed of an outer shell 7 closed at its ends by heads 8 and 9 35 of which the trunnions are a part, and a therewith coaxial inner shell 10.

The shells are connected in spaced relation to each other by distance bolts 12, the inner shell is for convenience in construction 40 and installation, longitudinally divided into a number of adjoining sections and the outer shell is provided with a lining 13 which for the same reasons is likewise made in sections.

Both the inner shell and the lining are 45 made of a hard, wear-resisting material while the outer shell is as usual made of ordinary iron.

The trunnions of the cylinder are hollow 50 for the passage of material to and from its interior, that at the feed end of the mill carrying a scoop 14 which dips into a supply-trough 15 and intermittently discharges its load into the trunnion.

The inner shell of the cylinder is spaced from the heads at the ends of the outer shell 55 for the connection of its interior with the space 16 between the shells.

At the discharge end of the mill the space between the inner shell and the adjacent head 9 is made of sufficient width to provide 60 a classifying chamber 17 in which the coarser material in the ground product is separated from the fines which pass through the hollow trunnion 4 as will hereinafter be more 65 fully explained.

The inner shell whose interior constitutes the grinding chamber 18 of the mill, is open at the feed end of the same and its opposite end is closed by a head 19 which has a central outwardly projecting spout 20 for the 70 discharge of the ground product into the classifying chamber.

The spout has, interiorly, a spiral groove 20^a winding reversely to the direction of rotation of the cylinder for the return of 75 balls which entered the same with the ground material, and a screen 21 at the outer end of the spout aids in preventing the passage into the classifying chamber of balls of larger size than its meshes. The mesh of the 80 screen is smaller than the width of the space 16 between the shells of the cylinder, so that balls which by wear have been reduced to a size which permits of their passing through the screen may freely move through said 85 space to reenter the grinding chamber at the feed end of the mill.

The annular space between the two shells is divided into helical channels winding 90 reversely to a fixed direction of rotation of the mill, by spiral ribs 22 which are continued within the classifying chamber.

The ribs are made up of series of sections divided by spaces which interconnect the different channels, and the sections of each 95 rib are placed in staggered relation to those of the next preceding and following ones so that there is no continuous longitudinal passage through the space between the shells and the material passing through the channels must drop from one to the other in what may be called a continuous cascade while constantly wending its way to the feed end of the mill.

An opening in the outer shell normally 105 closed by a plug 23, is provided for the dis-

charge of material remaining in the channels after the rotating cylinder is brought to a condition of rest.

A circular dividing plate or baffle 24 placed concentrically in the classifying chamber intermediate of the heads of the inner and outer shells, extends circumferentially in close proximity to the inner edges of the spiral ribs and is preferably mounted 10 upon adjusting screws 25 extending through the outer head, so that its distance from the heads may be regulated according to varying conditions.

A central opening in the baffle connects 15 with a pipe 26 extending through the hollow trunnion 4 and this pipe is by means of a swivel-union 27 connected with a conduit 28 leading from a conveniently located source of water supply.

20 In the operation of the mill, the cylinder 2 is rotated by the driving action of a pinion meshing with a gear wheel 29 fastened around the outer shell.

The pulp fed into the rotating cylinder 25 through the hollow trunnion 3 by means of the therewith connected scoop 14, passes into the inner shell where it is subjected to the triturating action of a mass of balls or pebbles which are constantly lifted to drop 30 back into the pulpy mass.

The ground product passing through the spout on the head of the inner shell, enters the classifying chamber and is by contact with the baffle compelled to move to the 35 outer circumference of the same before it enters the portion of the chamber between the baffle and the head of the outer shell.

The slimes floating to the surface of the liquid pass through the trunnion 4 into a 40 chute or other receptacle and the coarser material which settles in the lower portion of the chamber, moves through the spiral channels winding reversely to the direction of rotation of the cylinder, to the feed end of the mill where it reenters the inner shell for further grinding.

The material while passing through the channels, drops from one into the other through the staggered openings in their dividing walls and thereby prevents clogging which might occur if the channels were of 50 unbroken continuity.

The classification taking place in the chamber 17 is aided by a supply of water 55 through the pipe 26, which liberates the slimes and assists their ascending movement to the surface of the liquid constantly discharged through the trunnion 4 and which furthermore facilitates the return movement of the oversize to the feed end of the mill.

The baffle by breaking the current from the grinding chamber to the outlet of the mill, is also instrumental in producing a 60 clean separation of the fines from the coarser

matter and by varying its position with relation to the heads between which it is placed, the classifying action may be regulated in accordance with the requirements of different materials.

Any balls of ordinary size passing with the ground material into the spout, are prevented from entering the classifying chamber by the screen 21 and are returned into the grinding chamber by the screw-thread, 70 and balls which by wear have been reduced to a size which permits of their passing through the meshes of the screen, move with the oversize through the channels and are thus returned to the grinding chamber.

Although the ribs 22 have been shown in the drawings as formed integral with the lining of the outer shell they may be made separate therefrom and secured by bolts or rivets or they may be fastened to or made 85 integral with the inner shell as may be found to be most convenient.

Two or more baffles may be arranged in the classifying chamber in case it is found that a repeated deflection of the current of material is advantageous in obtaining a clean division of the slimes from the coarse material in the product of the mill, and other modifications in the construction and arrangement of the parts of the mill may be 95 resorted to within the spirit of the invention as defined in the hereunto appended claims.

When the operation of the mill is discontinued for any length of time, the material remaining in the interconnected channels may be withdrawn by turning the cylinder until the opening of the outer shell is at the bottom thereof and removing the plug which normally closes the opening.

It is essential that the opening of the trunnion 4 at the discharge end of the mill is of larger diameter than that of the spout 20 in the head of the inner shell to produce a constant outward current.

Having thus described my invention what I claim and desire to secure by Letters Patent is:

1. A grinding mill comprising a rotary cylinder having a classifying chamber at one end, a grinding chamber between the classifying chamber and its opposite end, an opening for the discharge of material from the classifying-chamber, an opening for the discharge of material from the grinding-chamber into the classifying-chamber, and a plurality of channels interconnected by staggered openings in their dividing walls, and winding reversely to a fixed direction of rotation of the cylinder, from the classifying-chamber, around the grinding chamber to and in connection with the opposite end of the same.

2. A grinding mill comprising a rotary cylinder having a classifying chamber at one

end, a grinding-chamber between the classifying-chamber and its opposite end, an opening for the discharge of material from the classifying-chamber, an opening for the discharge of material from the grinding-chamber into the classifying-chamber, a baffle spaced from the outer wall of the mill and within the same outside of the grinding-chamber and a spiral channel winding 5
versely to a fixed direction of rotation of the cylinder, from the classifying-chamber, around the grinding-chamber to and in connection with the opposite end of the same.

3. A grinding-mill comprising a rotary cylinder having a classifying-chamber at one end, a grinding-chamber between the classifying-chamber and its opposite end, an opening for the discharge of material from the classifying-chamber, an opening for the discharge of material from the grinding-chamber into the classifying-chamber, a baffle spaced from the outer wall of the mill and adjustably mounted within the same inside of the grinding-chamber, so that its distance 20
from the discharge-opening in the grinding-chamber may be varied, means for adjusting the position of the baffle, and a spiral channel winding reversely to a fixed direction of rotation of the cylinder, from the classifying-chamber, around the grinding-chamber to and in connection with the opposite 25
end of the same.

4. A grinding-mill comprising a rotary cylinder having a classifying-chamber at one end, a grinding-chamber between the classifying-chamber and its opposite end, an opening for the discharge of material from the classifying-chamber, an opening for the discharge of material from the grinding-chamber into the classifying-chamber, means 30
for introducing a liquid into the classifying-chamber, and a spiral channel winding reversely to a fixed direction of rotation of the cylinder, from the classifying-chamber, around the grinding-chamber to and in connection with the opposite end of the same.

5. A grinding-mill comprising a rotary cylinder having a feed-opening at one end and a classifying-chamber at its opposite end, an inner cylinder spaced circumferentially from the other outside of the classifying-chamber and the inner cylinder having an opening for the discharge of material into said chamber, and a channel winding 35
through the space between said cylinders reversely with relation to a fixed direction of rotation of the same, from the classifying-chamber at the one end of the outer cylinder, to and in connection with the portion of the inner cylinder at the opposite end of the same.

6. A grinding-mill comprising a rotary cylinder having a feed-opening at one end and a classifying-chamber at its opposite 40
end, an inner cylinder spaced circumferen-

tially from the other outside of the classifying-chamber and having an opening for the discharge of material into said chamber, and a plurality of intercommunicating channels winding through the space between said cylinders reversely with relation to a fixed direction of rotation of the same, from the classifying-chamber at the one end of the outer cylinder, to and in connection with the portion of the inner cylinder, at the opposite 45
end of the same.

7. A grinding-mill comprising a rotary cylinder having a feed-opening at one end and a classifying-chamber at its opposite end, an inner cylinder spaced circumferentially from the other outside of the classifying-chamber and having an opening for the discharge of material into said chamber, and a plurality of channels interconnected by staggered openings in their dividing walls, 50
and winding through the space between said cylinders reversely with relation to a fixed direction of rotation of the same, from the classifying-chamber at the one end of the outer cylinder, to and in connection with the portion of the inner cylinder, at the opposite 55
end of the same.

8. A grinding-mill comprising a rotary cylinder having a feed-opening at one end and a classifying-chamber at its opposite end, an inner cylinder spaced circumferentially from the other outside of the classifying-chamber and having an opening for the discharge of material into said chamber, and a channel winding through the space between 60
said cylinders reversely with relation to a fixed direction of rotation of the same, in connection with the inner cylinder at the feed-end of the mill, and continued within the classifying-chamber at the opposite end 65
of the same.

9. A grinding-mill comprising a rotary cylinder having a feed-opening at one end and a classifying-chamber at its opposite end, an inner cylinder spaced circumferentially 70
from the other outside of the classifying-chamber and having an opening for the discharge of material into said chamber, a channel winding through the space between said cylinders reversely with relation to a fixed direction of rotation of the same, in connection with the inner cylinder at the feed-end of the mill, and continued within the classifying-chamber at the opposite end 75
of the same, and a baffle in the classifying-chamber between the ends of the cylinders, and circumferentially, adjacent to the channels.

10. A grinding-mill comprising a rotary cylinder having a feed-opening at one end and a classifying-chamber at its opposite end, an inner cylinder spaced circumferentially from the other outside of the classifying-chamber and having an opening for the discharge of material into said chamber, a 80
125

channel winding through the space between said cylinders reversely with relation to a fixed direction of rotation of the same, in connection with the inner cylinder at the feed-end of the mill, and continued within the classifying chamber at the opposite end of the same, and a baffle in the classifying-chamber circumferentially, adjacent to the channels and mounted for adjustment to vary its distance from the discharge-opening of the inner cylinder.

11. A grinding mill having a feed-opening and a discharge-opening respectively at its opposite ends, and interiorly a classifying chamber at its discharge-end, and a grinding chamber between the classifying-chamber and the feed-end of the cylinder having a central opening for the discharge of material into the classifying chamber, there being a passage around the grinding chamber connecting its end at the feed-end of the cylinder, with the classifying cham-

ber, and a baffle spaced from the discharge opening of the grinding chamber and, peripherally, from the wall of the outer cylinder, inside of the classifying chamber. 25

12. A grinding-mill comprising a rotary cylinder having a feed-opening at one end and a classifying space at its opposite end, an inner cylinder spaced circumferentially 30 from the other outside of the classifying space and having a central opening for the discharge of material into said classifying space, the space between said cylinders communicating at one end with the classifying space, and at its opposite end with the interior of the inner cylinder, and a baffle spaced from the discharge-opening of the inner cylinder, and, peripherally from the wall of the outer cylinder, inside of the 35 classifying space. 40

In testimony whereof I have affixed my signature.

JOSEPH S. BARTLEY.
